UNITED STATES PATENT OFFICE.

HECTOR LE DOUX, OF WORCESTER, MASSACHUSETTS, ASSIGNOR TO CROMPTON & KNOWLES LOOM WORKS, A CORPORATION OF MASSACHUSETTS.

LOOM-DOBBY.

935,667.

Specification of Letters Patent.

Patented Oct. 5, 1909.

Application filed October 24, 1907. Serial No. 398,995.

To all whom it may concern:

Be it known that I, HECTOR LE DOUX, a citizen of the United States, residing at Worcester, in the county of Worcester and State of Massachusetts, have invented certain new and useful Improvements in Loom-Dobbies, of which the following is a specification.

My invention relates to a loom dobby for 10 operating the harnesses of a loom, and more particularly to a dobby for a loom having swivel shuttles, to obtain a figured effect in plain or fancy weaves, in addition to the ordinary fly shuttle.

15 In looms of the class referred to, ordinarily termed swivel looms, there are one or more rows of swivel shuttles operated by racks at predetermined times, according to the indications of the pattern chain, to obtain a figured effect. In this class of looms, as ordinarily made, the harnesses are moved to form the shed for the swivel shuttles, and also moved to form the shed for the fly shuttle, and the swivel shuttles are operated 20 at one time, when the picking motion for the general fly shuttle has to be stopped, and the fly shuttle is operated at another time. For example, when the woven fabric has a series of continuous stripes made by the 25 swivel shuttles, said shuttles are operated every other pick, and the picking motion for the fly shuttle has to be stopped every other pick, so that the amount of the fabric produced is only half as much as it would be, according to the speed of the loom, as if 30 there were a simultaneous operation of the swivel shuttles, and of the fly shuttle.

The object of my invention is to improve upon the construction of a dobby of the 40 class referred to.

In my improvements I form simultaneously a double shed, a lower and larger shed for the fly shuttle, and an upper and smaller shed for the swivel shuttles when the swivel 45 shuttles are to be operated. The swivel shuttle rail may be attached to the hand-rail of the lay in any suitable or usual way, and when the swivel shuttles are operated, they carry the filling through the upper shed, and 50 the fly shuttle carries the filling through the lower shed, simultaneously, and thus the

woven fabric will be produced without losing a pick.

In my improvements, in order to obtain a double shed when desired, I provide each 55 upper hook and each lower hook operated by the two lifter bars, with two notches, making a double hook. I also provide some of the pattern chain bars with pegs of different lengths. When the pattern chain bar 60 has no peg, the pattern indicator finger will raise a dobby hook, and there will be no movement of the harness jacks, thus leaving a certain amount of the warp threads in the lower plane of the shed, as usual, and when 65 a short peg comes under the pattern indicator finger, the outer notch or hook on a dobby hook will be engaged by a lifter bar, and the warp threads moved to the middle position, thus forming the upper part of the 70 shed for the fly shuttle, as well as the lower part of the shed for the swivel shuttles, and when a long peg on the pattern chain bar comes under a pattern finger, the dobby hook will drop down, and the lifter bar will engage 75 the inner hook of the double hook, and move the warp threads up to their highest position, to form the upper part of the shed for the swivel shuttles.

In my improvements, I preferably use a 80 mutilated gear drive, instead of a crank drive, for the dobby rocking lever of the lifter bars, to obtain a quick motion in the shed opening, and also a long dwell for the shed, to give time for the movement of the 85 swivel shuttles.

I have shown in the drawings a detached portion of a loom dobby with my improvements combined therewith, sufficient to enable those skilled in the art to understand 90 the construction and operation thereof.

Referring to the drawings:—Figure 1 is a side view of a dobby, and a portion of a loom side, with my improvements combined therewith. Fig. 2 shows the mutilated gear 95 drive shown in Fig. 1, detached, and as a section on line 2, 2, Fig. 1, looking in the direction of arrow a, same figure. Fig. 3 shows the inner part of the dobby, detached, with the jacks and hooks forming a double 100 shed. Fig. 4 corresponds to Fig. 3, but shows a different position of some of the

parts for the formation of the lower shed only, for the fly shuttle. Fig. 5 shows the position of a double hook, when lowered through a long peg on the pattern chain. 5 Fig. 6 shows the position of a double hook when lowered through a short peg, and, Fig. 7 shows the position of a double hook when there is no peg on the pattern chain.

In the accompanying drawings, 1 is a 10 datched portion of a loom frame, 2 is the dobby stand, 3 are the harness levers or jacks, pivotally mounted on a transverse rod 4, each jack 3 carrying a hook lever 5, pivotally mounted thereon, to the upper end of 15 which is pivotally attached the upper hook 6, and to the lower end of which is pivotally attached the lower hook 7. Each hook 6 and 7, has on one end, on one side or edge two notches forming two hook portions 6' 20 and 6'', and 7', and 7'', respectively.

8 is the upper lifter bar, which has a reciprocating movement in a horizontal opening 2' in the frame 2 of the dobby, and is connected at each end by a link 9 with the 25 dobby rocking lever 10, centrally mounted on a shaft 11. The lower lifter bar 12 has a reciprocating movement in an elongated slot 2'' in the frame 2, and is connected by a link 13 to the lower end of the lever 10.

30 14 is a pattern cylinder, carrying the pattern chain, made up of bars 15, in this instance carrying long pegs 15', and short pegs 15'' on the same bar, and also short pegs 15''' on another bar. Extending over the 35 pattern cylinder 14 are the pattern indicator fingers 16, some of which have straight inner ends, on which rest the upright wire 17, to raise or lower the upper hooks 6, and the others having the upturned inner ends 40 16', to engage and raise the lower hooks 7. The pattern chain cylinder 14 has a rotary movement communicated thereto through a worm gear 18 meshing with and driven by a worm 19 fast on a shaft 20. The shaft 20 45 carries a bevel pinion 21, which meshes with the bevel pinion 22 on the upright shaft 23. The lower end of the upright shaft 23 has a bevel pinion 24 thereon, which meshes with a bevel pinion 25 on a driven shaft 26. 50 All of the above mentioned parts, except the double hooks 6, and 7, may be of the usual and well known construction.

The lever 10 has an arm 10', and an elongated opening 10'' therethrough, in which 55 is adjustably secured the upper end of a rod 27. The lower end of the rod 27 is mounted on a crank stud 27' on a gear 28 which is mounted on a stud 29 and carries a plate 30, which has concaved ends to travel on 60 an annular flange 31' on a mutilated gear 31, to form a dwell gear drive for the dobby rocking lever 10. The mutilated gear 31 is fast on the driven shaft 26.

The operation of my improvements, from

the above description in connection with the 65 drawings, will be readily understood by those skilled in the art. In the revolution of the pattern cylinder 14, if a pattern chain bar 15 has no peg thereon, a pattern indicator finger 16 will drop down at its 70 weighted end, and raise a double hook 6, or 7 out of engagement with the lifter bars 8 and 12, as shown in Fig. 7, so that there will be no movement of the harness jacks 3, leaving a certain amount of warp threads in 75 the lower plane of the shed, as usual. When a short peg 15'' comes under a pattern indicator finger 16, the outer hook, of a hook 6, or 7, will be engaged by the lifter bar, as shown by broken lines in Fig. 6, and the 80 harness jacks 3 will be operated to move the warp threads to the middle position, thus forming the upper part of the shed for the fly shuttle, as well as the lower part of the shed for the swivel shuttles. When a long 85 peg 15' comes under a pattern indicator finger 16, a hook 6, or 7 will move down, as shown in Fig. 5, so that the inner hook will be engaged by the lifter bar, and move the harness jacks 3 to cause the warp threads 90 to be moved to the highest position, to form the upper part of the shed for the swivel shuttles. In this way, the two sheds, a lower shed for the fly shuttle, and an upper shed 95 for the swivel shuttles, are formed simultaneously when desired, and both the swivel shuttles and the fly shuttle will be operated simultaneously, and there is no stopping of the picking motion. By means of the mutilated gear drive for the dobby operating 100 lever 10, I obtain a quick motion in the shed opening, and also obtain a long dwell for the shed, to give time for the passage of the shuttles.

It will be understood that the details of 105 construction of my improvements may be varied if desired.

Having thus described my invention, what I claim as new and desire to secure by Letters Patent is:—

1. In a loom dobby, a pattern chain, pattern indicator fingers, connections between said indicator fingers and the hooks operated by the lifter bars, and said hooks, having two notches thereon forming a double hook for coöperation with a single lifter bar, the hook levers pivotally mounted on the harness jacks, and said harness jacks, and lifter bars, and means for operating said lifter bars.

2. In a loom dobby, a pattern chain made up of bars having pegs thereon of two different lengths, pattern indicator fingers, connections between said indicator fingers and the hooks operated by the lifter bars, and said hooks, having two notches thereon forming a double hook for coöperation with a single lifter-bar, the hook levers pivotally

mounted on the harness jacks, and said harness jacks, and lifter bars, and means for operating said lifter bars.

3. In a loom dobby, the combination with 5 the lifter bars for operating the hooks, and said hooks, having two notches, thereon forming a double hook, and the rocking lever for said bars, of means for operating said lever, said means comprising a driven

mutilated gear, meshing with a gear, and 10 said gear, carrying a dwell plate, and a crank pin, and connections from said crank pin to said operating lever.

H. LE DOUX.
